[57] CLAIM

The ornamental design for a combined liquid detergent dispensing gun and liquid detergent holder, as shown and described.

DESCRIPTION

FIG. 1 is a front elevational view of a combined liquid detergent dispensing gun and liquid holder detergent showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front top perspective view thereof; and,

FIG. 8 is an upside-down bottom perspective view thereof.

The dispensing gun and detergent holder are shown separately for convenience of illustration in FIGS. 1-8.
